CHILD'S STROLLER

Paul Barela, North Hollywood, Calif.

Application February 15, 1954, Serial No. 29,008

Term of patent 3½ years

(Cl. D34—15)

To all whom it may concern:

Be it known that I, Paul Barela, a citizen of the United States, residing in North Hollywood, California, have invented a new, original, and ornamental Design for a Child's Stroller, of which the following is a specification, reference being had to the accompanying drawing, forming part thereof.

Fig. 1 is a top plan view of a child's stroller, showing my new design.

Fig. 2 is a side elevational view thereof.

Fig. 3 is a bottom plan view to a reduced scale with the propelling handle omitted.

The dominant features of the design reside in the portions shown in full lines in the drawing.

I claim:

The ornamental design for a child's stroller, substantially as shown and described.
